(Cl. D86—10)

To all whom it may concern:

Be it known that we, Charles H. Foster and Hertha Furth, citizens of the United States, residing in New York city, in the county of New York and State of New York, have invented a new, original, and ornamental Design for a Combined Perfume Bottle and Support, of which the following is a specification, reference being had to the accompanying drawing, forming a part thereof.

In the drawing:

We claim:

The ornamental design for a combined perfume bottle and support, as shown.

CHARLES H. FOSTER.
HERTHA FURTH.
